Des. 179,400

Patented Dec. 11, 1956

179,400

TOY LOCOMOTIVE CAB

Robert E. Svozil, East Paterson, N. J.

Application February 2, 1956, Serial No. 40,007

Term of patent 7 years

(Cl. D34—15)

Fig. 1

Fig. 2

Fig. 3

Fig. 4

Fig. 5

Figure 1 is a right side elevational view of a toy locomotive cab, showing my new design;

Figure 2 is a left side elevational view;

Figure 3 is a front elevational view;

Figure 4 is a rear elevational view; and

Figure 5 is a top plan view.

I claim:

The ornamental design for a toy locomotive cab, as shown.
